(57) **CLAIM**

We claim the ornamental design for a hard shell, multi-article, reclosable packaging, as substantially shown and described.

DESCRIPTION

FIG. 1 is a front perspective view of a hard shell, multi-article, reclosable packaging in accordance with the present design. The reclosable packaging is adapted to contain multiple articles of a consumable product such as chewing gum. The packaging includes a base enclosure and a reclosable lid shown in FIG. 1 in an opened positon.

FIG. 2 is a front elevational view of the reclosable packaging shown in FIG. 1.

FIG. 3 is a top view of the reclosable packaging shown in FIG. 1. Features disclaimed with broken lines in FIG. 3 indicate structure which forms no part of the claimed design

FIG. 4 is a right side elevational view of the reclosable packaging shown in FIG. 1.

The left side elevational view of the reclosable packaging shown in FIG. 1 is the mirror image of FIG. 4.

FIG. 5 is a rear elevational view of the reclosable packaging shown in FIG. 1.

FIG. 6 is another top front perspective view of the reclosable packaging shown in FIG. 1 in accordance with the present design, but with the reclosable lid being shown in a closed position.

FIG. 7 is a front elevational view of the reclosable packaging shown in FIG. 6.

FIG. 8 is a top view of the reclosable packaging shown in FIG. 6.

FIG. 9 is a right side elevational view of the reclosable packaging shown in FIG. 6; and,

The left side elevational view of the reclosable packaging shown in FIG. 6 is the mirror image of FIG. 9.

FIG. 10 is a rear elevational view of the reclosable packaging shown in FIG. 6.
